UNITED STATES PATENT OFFICE.

CHRISTOFFER A. CHRISTENSEN, OF PORTLAND, OREGON, ASSIGNOR TO THE INTERNATIONAL MINING & MILLING CO., OF PORTLAND, OREGON.

CENTRIFUGAL CONCENTRATOR.

1,081,267.

Specification of Letters Patent. Patented Dec. 9, 1913.

Application filed June 20, 1912, Serial No. 704,830. Renewed June 2, 1913. Serial No. 771,337.

To all whom it may concern:

Be it known that I, CHRISTOFFER A. CHRISTENSEN, a citizen of the United States, residing at Portland, in the county of Multnomah and State of Oregon, have invented certain new and useful Improvements in Centrifugal Concentrators; and I do declare the following to be a full, clear, and exact description of the invention, such as will enable others skilled in the art to which it appertains to make and use the same.

This invention relates to separators, and more especially to those wherein the concentrates are separated from the tailings by centrifugal action; and the object of the same is to improve the construction of a machine of this character and greatly simplify the same while increasing the output.

The objects are accomplished by building the machine in the manner hereinafter more fully described and claimed, and as shown in the drawings wherein—

Figure 1 is a central vertical section through this machine complete, and Figs. 2 and 3 are cross sections on the lines 2—2 and 3—3 of Fig. 1.

In the preferred embodiment of my invention shown in the drawings attached, a framework 1 supports a fixed launder trough 2 for the tailings or waste, the same having a suitable outlet 5 and a closed top with a rather wide flange 8 projecting inward over and spaced above the inner wall 3 of the trough so as to leave an annular inlet 9 between them.

Mounted in suitable bearings 10 and 11 within the framework is an upright shaft 12 which may be rotated in any suitable manner, as by having a power wheel 13 connected by belt with a suitable source of energy; and secured to said shaft are spiders 20 carrying an upright cylinder 21 whose open upper end or mouth stands adjacent the inlet 9 into the launder and whose lower end carries a ring shaped head 25 having a central opening 26. Through the latter projects an upright sleeve 27 surrounding the lower end of the shaft 12 and its step bearing 11 and keeping them clean, which sleeve 27 rises from the bottom of a cylindrical inlet member or pan through whose walls at different levels are connected the outlet and inlet pipes 28 and 29 as shown. The former opens from the annular space 30 around the sleeve 27 and above a false bottom 31, and

such space is in communication through the open top of the pan with the opening 26 at the lower end of the cylinder. The inlet pipe 29 communicates with the annular space 32 around the sleeve 27 below said false bottom 31 and above the true bottom 33 of the pan, and from the false bottom rise several pipes 34 which extend upward throughout the height of but not in communication with the annular space 30, and then still farther upward through the opening 26 with their upper ends 35 deflected radially outward within the cylinder above its lower head 25. Thus the annular space 30 constitutes a second launder or trough for receiving the values which pass off the head 25 and through the opening 26 and are drawn off at 28 in a manner indicated by the arrows; whereas the space 32 is a part of the feed inlet, because the material fed in through the pipe 29 passes around within this space and is delivered through the several pipes 34 into the lower portion of the cylinder above its head 25. A perforated water pipe 36 is carried by and beneath said flange 8, and the supply of water thereto may be regulated so that its perforations deliver water onto the interior of the cylinder in quantities and at times regulated by the cock 37 or in any suitable way.

The operation of the invention is as follows: A solution of ground ore and water in proper proportions (slime or pulp) is fed through the feed pipe 29 and passes up the pipes 34 into the cylinder wherein it is driven radially outward by centrifugal force. While it is possible to insert a liner within the cylinder as indicated at 40 in Fig. 1, I prefer to mix the pulp to such consistency and speed up the cylinder to such a degree that the pulp will accumulate within the cylinder to form its own liner, the grade from the bottom of the cylinder upward being about 5%. However, whether the liner is inserted separately or is built up in this manner, after it becomes established the water and lighter materials pass upward over its inner face under the influence of centrifugal force, over the edge of the cylinder as at 9, and into the waste trough or launder 2; while the minerals or heavier particles accumulate against the inner face of the liner and do not flow off with the lighter particles because of their 110

greater specific gravity. After running the machine for a certain length of time, according to the amount of minerals contained in the ore, it will have built up an inner wall 5 or liner consisting of minerals and coarser sand. The speed of rotation is then reduced, and water turned on from the pipe 36 and sprayed down within the cylinder so as to wash the concentrates and all the minerals 10 that have banked on the inside down into the launder trough 30. Thereafter the water is turned off, the speed of rotation again increased, more slime or pulp fed to the machine, and the operation is repeated. The 15 concentrates thus washed out into the launder 30 will be found to consist of sand, grit, and fine minerals; and after being cleaned, a good product is produced and from which the minerals can be separated easily on a 20 table by any of the well known processes. For different ores or ores of different grades and weight, and perhaps on account of other conditions, the speed of rotation may be varied as the necessity of the case will require, and also the volume of water may be varied as the expert operator will soon discover.

The entire machine is of a size proportionate to the work to be accomplished, and 30 its materials and specific construction are matters of no moment, as changes therein may be made so long as the spirit of the invention is retained.

What is claimed as new is:—

35 1. In a centrifugal separator, the combination with an upright rotary cylinder whose lower end carries a ring-shaped head, and an axial shaft supporting said cylinder; of an open-topped pan disposed below the 40 cylinder with its upper edge standing under said head, a false bottom therein producing a lower space, a feed pipe communicating with this space, a plurality of pipes extending through said false bottom from this 45 space upward through the opening in said ring-shaped head of the cylinder and hav-

ing their upper ends directed radially outward within the latter, an outlet pipe for the values opening through the wall of the pan above said false bottom, an upstanding sleeve rising from the true bottom of the pan through its false bottom and closing the lower end of said shaft, and a bearing within said sleeve in which the lower extremity 50 of said shaft is stepped. 55

2. In a centrifugal separator, the combination with an upright rotary cylinder whose lower end carries a ring-shaped head, of an open-topped pan beneath the cylinder whose upper end stands beneath said head, 60 a false bottom therein producing a lower space, a feed pipe communicating with this space, a plurality of pipes extending through said false bottom from this space upward and communicating with the interior of the 65 cylinder, and an outlet pipe for the values opening through the wall of the pan above said false bottom, substantially as described.

3. In a centrifugal separator, the combination with an upright rotary cylinder, and 70 an axial shaft supporting the same, of an open-topped pan disposed below the cylinder and having a central upstanding sleeve surrounding the lower end of said shaft, a false bottom within said pan producing a 75 lower annular space around said sleeve, a feed pipe communicating with this space, a plurality of feed pipes rising from said space through this false bottom and extending upward into the cylinder, and an exhaust pipe for the values communicating with the annular space around said sleeve and above said false bottom, substantially as described.

In testimony whereof I have hereunto set 80 my hand in presence of two subscribing witnesses.

CHRISTOFFER A. CHRISTENSEN.
